TRIMMER MECHANISM FOR SEWING
MACHINESFrederic M. Card, Bridgeport, Conn., assignor to
The Singer Manufacturing Company, Eliza-
beth, N. J., a corporation of New Jersey

Application May 25, 1935, Serial No. 23,357

4 Claims. (Cl. 112—125)

This invention relates to improvements in work-severing devices for sewing machines and is particularly adapted for use in connection with hemstitching machines for severing the cross-bars of a hemstitch seam in the production of picot-edging.

The primary object of the present invention is to provide a work-severing device of simple construction and arrangement whereby a movable cutting knife may be conveniently rendered ineffective.

With the above and other objects in view, the invention consists in the work-severing device hereinafter described in connection with the accompanying drawings which illustrate a preferred embodiment of the invention.

In the drawings, Fig. 1 is a front end elevation of the bracket-arm head of a hemstitching machine containing the improved work-severing device, the left presser-foot being partly broken away and the work-support being shown in section. Fig. 2 is a rear side elevation, partly in section, of a portion of the machine. Fig. 3 is a top plan view, partly in section, illustrating the severing device in its operative relation to the presser-foot of the machine. Fig. 4 represents, in perspective, the component parts of the cutting knife and its carrier in disassembled relationship. Fig. 5 is a detail sectional view, on a large scale, of the knife-holder securing means.

Referring to the drawings, the present invention is illustrated as embodied in a two-needle hemstitching machine constructed substantially as disclosed in the U. S. patent to G. M. Eames et al., No. 1,721,072, July 16, 1929. In general, this hemstitching machine has a work-support including a bed-plate 1 and a throat-plate 2 provided with a front-piercer aperture 3, a combination needle-and-piercer slot 4, and a knife-clearance slot 5 rearwardly of the slot 4. The work is advanced by a feed-dog 6 having spaced sections operating through suitable slots provided in the throat-plate at opposite sides of the slots 4 and 5.

Overhanging the cloth-plate 1 is a bracket-arm 7 terminating in a head 8. Rotatably journaled in said bracket-arm is a horizontally disposed actuating shaft 9 operatively connected to vertically reciprocate a needle-bar 10 in suitable bearings provided in the head 8. Fulcrumed upon a bracket 11 carried by the lower end of the needle-bar 10 are laterally spaced needle-holders 12, each carrying a needle 13. Secured to said needle-holders 12 are guide-rods 14 to which vibratory movements are imparted by operative

connections with endwise reciprocatory pitmen 15, disposed at the rear side of the bracket-arm as more fully disclosed in said prior Patent No. 1,721,072. A front piercer 16 is illustrated as carried by the needle-bar bracket 11 in position to enter the throat-plate aperture 3. The stitch-forming mechanism includes suitable loop-takers (not shown) which cooperate with the needles 13 below the throat-plate.

The bracket-arm head 8 is provided with suitable bearings for the usual vertically movable presser-bar 17 carrying presser-feet 18 which are opposed to the work-engaging sections of the feed-dog 6. The work-engaging portions of said presser-feet 18 are laterally spaced from each other to expose therebetween the throat-plate slots 4 and 5, and the front piercer aperture 3.

Also vertically movable in suitable bearings provided in the bracket-arm head 8 is a piercer-bar 19, to the lower end of which is secured a holder 20 for a piercer 21. Secured upon the piercer-bar 19 is a collar 22 to which is operatively connected a crank-arm 23 carried by a horizontally disposed rock-shaft 24 journaled in bearing lugs 25 and 26 at the rear side of the bracket-arm 7. The rock-shaft 24 carries another crank-arm 27 pivotally connected to one end of a pitman 28, of which the opposite end is provided with a strap embracing an eccentric 29 carried by the needle-reciprocating shaft 9. The piercer 21 is thus reciprocated vertically and serves to shape the work-apertures which separate the cross-bars of the usual hemstitch seam.

The present invention resides more particularly in an improved work-severing device. Secured by screws 30 upon the front end of the head 8 is a primary bracket 31 from which depends a supporting bar 32. Clamped upon the bar 32, for vertical adjustment, is a split boss 33 of an auxiliary bracket 34 having its rearward face recessed to provide a seat for a horizontally disposed member 35 of an angular supporting arm 35, 36. The arm-member 35 is secured by screws 37 to the bracket 34 for adjustment crosswise of the line of seam formation. The member 36 of the supporting arm depends from the bracket 34 and terminates at its lower end in a horizontally apertured bearing-boss 38 close to but spaced from the work-support sufficiently to provide work clearance.

Journaled in the bearing-boss 38 is a fulcrum-pin 39 extending laterally from a vertically vibratory lever 40 provided in a side face thereof and lengthwise of said lever with an arcuate guideway 41. The lever 40 extends rearwardly

from its fulcrum-axis and at its rearward end has an apertured ear 42 pivotally connected to the lower end of a link 43, of which the upper end is pivotally connected to a crank-arm 44 5 suitably secured upon the piercer-actuating rock-shaft 24. The guideway 41 preferably has its longitudinal center line passing vertically above the fulcrum-axis 39 of the lever 40.

Shiftable lengthwise of the lever 40, in the 10 guideway 41 thereof is a knife-carrier 45 having an aperture 46 receiving the shank of a threaded bolt 47 which passes through an arcuate slot 48 extending lengthwise of the side wall of the lever guideway 41. The slabbed head of the bolt 47 15 is slidingly disposed in the lever slot 48. Threaded upon the bolt 47 is a nut 50 which is recessed at its inner end to house a coil-spring 51 embracing the shank of said bolt. The spring 51 serves to retain the knife-carrier 45 in the lever- 20 guideway 41 when the nut 50 is slightly loosened, thereby providing for conveniently shifting the knife-carrier 45 in said guideway 41.

The knife-carrier 45 has a split forward end to receive the shank of a knife 52 having a vertically disposed and substantially straight cutting edge 53, the knife-shank being detachably secured to its carrier by means of screws 54. In its forward or operative position, the knife 52 depends into the slot 5 of the throat-plate 2, the 25 cutting edge 53 of said knife being opposed to the direction of feed of the work and being vibrated in substantially the vertical plane containing the center line of the hemstitch seam as it is formed.

30 It will be readily understood that as the work is advanced by the feeding mechanism of the machine past the stitch-forming mechanism thereof, the cross-bars of the hemstitch seam are brought into engagement with and are severed by the vibrating knife 52 rearwardly of the point of seam formation. The knife 52 may be shifted 35 into an ineffective position by sliding the knife-carrier 45 in the vertical plane of the knife edge 53 and in a direction rearwardly in the lever-guideway 41, relatively to the fulcrum-axis 39 of said lever. The curvature of the guideway 41 is such that when the carrier 45 is shifted rearwardly thereof, the knife 52 is correspondingly moved rearwardly and also upwardly out of the 40 throat-plate slot 5, so that in its ineffective position the lower portion of the knife-edge 53 is located above the lower face of the bearing boss 38 of the supporting-arm 36 and closely adjacent to the fulcrum-axis 39 of the lever. The knife 52 is therefore shiftable into an ineffective position wherein the knife-edge 53 is protected against being caught by the work. The nut 50 provides convenient manually engageable means for shifting the knife-carrier 45 in its guideway 41.

Having thus set forth the nature of the invention, what I claim herein is:—

1. A trimmer mechanism for sewing machines comprising, an actuating lever vibratory about a fulcrum-axis and provided with an arcuate 15 guideway, a work-severing knife, and a knife-carrier slidably mounted in said guideway providing for shifting movement of said knife out of and into operative positions thereof.

2. In a sewing machine, a work-support including a throat-plate having a needle-aperture, stitch-forming and work-feeding mechanism, a work-severing knife having its cutting edge disposed rearwardly of the throat-plate needle-aperture in a vertical plane through said needle-aperture, a vibratory actuating lever provided with a guideway extending lengthwise of said lever, a carrier for said knife shiftably disposed in said guideway, and means for vibrating said lever.

3. In a sewing machine, a horizontally disposed work-support, stitch-forming mechanism, work-feeding mechanism, a supporting bracket, a lever fulcrumed upon said bracket for vibratory movement about a horizontal-axis transverse to the direction of feed of the work, an arcuate guideway extending lengthwise of said lever, a knife-carrier shiftably secured in said guideway, and means for vibrating said lever.

4. A trimmer mechanism for sewing machines comprising, a vibratory lever provided with a guideway and with a slot extending longitudinally of said guideway, a knife-carrier slidably disposed in said guideway and provided with an aperture in alignment with said slot, a bolt extending through said slot and aperture, a knife-carrier securing nut threaded upon said bolt, and a spring housed by said nut in yielding engagement with said knife-carrier.
